(57) **CLAIM**

(21) Appl. No.: **29/258,012**

The ornamental design for a terminal for providing an electronic conduction in a connector, as shown and described.

(22) Filed: **Apr. 14, 2006**

DESCRIPTION

(51) LOC (8) Cl. **13-03**

FIG. 1 is a perspective view of a terminal for providing an electronic conduction in a connector showing my new design;

(52) U.S. Cl. **D13/148**; D13/133

FIG. 2 is a front elevation view thereof;

(58) Field of Classification Search D13/133,

FIG. 3 is a back elevation view thereof;

D13/148, 154, 184, 199; 439/866, 868, 874,
439/883-884, 894

FIG. 4 is a left side elevation view thereof;

See application file for complete search history.

FIG. 5 is a right side elevation view thereof;

(56) **References Cited**

FIG. 6 is a top plan view thereof; and,

U.S. PATENT DOCUMENTS

FIG. 7 is a bottom plan view thereof.
